W. MOULTRIE.

Hot Air Furnace.

No. 18,054.

Patented Aug. 25, 1857.

UNITED STATES PATENT OFFICE.

WILLIAM MOULTRIE, OF NEW YORK, N. Y.

WATER VESSEL FOR IMPARTING HUMIDITY TO HOT AIR AND VAPOR-DRAFT TO THE GRATE-BARS OF HOT-AIR FURNACES.

Specification of Letters Patent No. 18,054, dated August 25, 1857.

To all whom it may concern:

Be it known that I, WILLIAM MOULTRIE, of the city, county, and State of New York, have invented certain new and useful Improvements in Furnaces, Stoves, and other Heating Apparatus, of which the following is a description, reference being had to the accompanying drawings as forming part of this specification.

10 Figure 1 is a perspective view of the brick furnace chamber, showing on its front face, the coal (E) and ash-pit (G) doors. Fig. 2 is a vertical section of the apparatus cut through at its center. Fig. 3 is a horizontal section, cut through just above the grate bars.

Letter A represents the chamber of brick inclosing the apparatus. Letters B represents the openings from this chamber to the 20 flues, for conducting the warm air to the various parts of the house.

Letter C (Fig. 2,) represents the body or fire chamber of the furnace.

Letter D represents the pipe for the escape 25 of smoke to the chimney.

Letter E represents the door or entrance for the admission of fuel to the fire.

Letter F represents the ash-pit and G the door from the outer air leading thereto.

30 Letter H (Fig. 1,) represents the door at the side leading to the interior of the furnace chamber.

Letter J represents a hollow chamber, next contiguous to the fire chamber, formed 35 in the space existing between the projecting doors E and G.

Letter K represents a sliding register in the ash-pit door G for the admission of cold air to the grate bars. Letter L represents a similar register leading to the 40 hollow chamber J for the admission of air thereto.

Letter M represents a hollow vessel or chamber in the interior, adjacent to the 45 ash-pit and opposite in situation to the ash-pit door for containing water (R) having a movable lid or cover (N) Fig. 2. Letter O represents an opening from this vessel (M) to the ash-pit having a sliding register 50 opening and shutting at pleasure. Letter P represents another adjustable opening from the interior of the furnace chamber to the water vessel (M). Perforations or 55 openings (Q) are also made in the roof of the projecting part of the ash-pit, leading

from the hollow chamber (J) to the ash-pit.

By opening the register L and shutting the register K, the only avenue for the admission of air to the grate bars, for the 60 support of combustion, is through the hollow chamber J, and through the perforations (Q) in the ceiling of the projecting ash pit. The air in its descent becomes heated by contiguity and contact with the 65 heated sides and interior of the chamber J, before its admission to the burning fuel. Its descent is indicated by the arrows (Fig. 2). To insure the certain heating of the air currents, the hollow chamber J may be filled 70 with wire work or other equivalent metallic interstices, as shown in Figs. 2 and 3. The use of warm air for the support of combustion is well known and need not be further described.

75 My improvement more particularly relates to the application and employment of the water vessel M in the vicinage of the ash pit or fire chamber so that the water therein (R) may be heated, and vaporization produced thereby. The steam or vapor arising therefrom, is supplied to the grate bars through the register O, for the better support of combustion. I make such vessel (M) with a lid or cover (N), removable at 80 pleasure, for the better filling of the same with water. A pipe however may lead from said vessel to the outside of the furnace chamber, into and through which the required water may be poured. Immediately 85 above the water level, and in the side of the ash pit, next contiguous to the vessel (M), I make the adjustable openings with a register (O), above referred to. Similar openings may lead from the vessel (M) to the 90 interior of the furnace chamber, as shown by the register at P, so that the warm air of the furnace chamber may be admitted over the surface of the water, to the ash pit, conveying with its currents the steam 100 or vapor generated by the water. By shutting the register (O) and allowing the register P to remain open, or by removing the lid N, the water vessel (M) becomes 105 useful as a water pan for communicating moisture to the heated air within the furnace chamber, thus rendering it more wholesome for distribution throughout the house.

I do not claim the placing of a water vessel within a furnace chamber simply for 110

the purpose of imparting humidity to the air therein, nor do I claim to have discovered the utility of vapor draft for the support of combustion. But

5 What I do claim as my own invention and desire to secure by Letters Patent of the United States, is—

The structure, location and application of the water vessel M whereby either, or

both of said objects are attained, substantially as hereinbefore described, in connection with furnaces and other heating apparatus.

WM. MOULTRIE.

In presence of—

THOS. PALMER,
JOHN BEAVER.
